UNITED STATES PATENT OFFICE.

JOHN EVANS CORNELL, OF CHICAGO, ILLINOIS, ASSIGNOR, BY MESNE ASSIGNMENTS, TO BATES VALVE BAG COMPANY, OF CLEVELAND, OHIO, A CORPORATION OF WEST VIRGINIA.

BAG.

No. 895,435.

Specification of Letters Patent.

Patented Aug. 11, 1908.

Application filed July 23, 1903. Serial No. 116,239.

To all whom it may concern:

Be it known that I, JOHN EVANS CORNELL, a citizen of the United States, residing at Chicago, in the county of Cook and State of Illinois, have invented a certain new and useful Improvement in Bags, of which the following is a specification.

My invention relates to bags, particularly such as are intended to be filled with powdery or granular substances, and which are designed to be produced in the bag factory in a substantially complete form, and to be then filled and closed without recourse to the ordinary methods of closing the bag, such as 15 sewing, tying or the like.

In the accompanying drawings I have illustrated one form of my invention, for a single form will be sufficient to illustrate the same, though I wish it to be understood that 20 the form shown is only one of many.

Figure 1 is a side elevation of a bag of my invention, filled. Fig. 2 is a plan view of the same. Fig. 3 is a cross section on the line 3—3 of Figs. 1 and 2. Fig. 4 is a side elevation of the bag showing the parts during the process of filling. Fig. 5 is an elevation of the same showing the filling opening with the filling tube removed.

Like parts are indicated by the same letter 30 in all the figures.

A A are the side portions of the bag and B B the edge portions. These two sides and two edges may, of course, be composed of a single piece of material, or of several pieces properly 35 united. The ends of the bags are composed of four overlapping pieces, each being an extension of its associated edge or side. For convenience I have lettered these portions, which I will call "flaps" as follows: C is the 40 outer flap, associated with one of the sides A and C' is the under flap associated with the other side. C' is the upper flap associated with one of the edges B, and C'' is the under flap associated with the other edge. It is 45 understood, of course, that the division of the elements of the bag into ends, edges, flaps, sides and the like, is not so much to distinguish these several parts, which may be like the common corresponding portions, but for 50 convenience in describing the bag and its use and operation. It is understood, of course, that the bag folds out into a flat package when emptied and the several creasing lines D D indicate the creases or folds formed when

the bag is collapsed into a flat condition. 55 Preferably the bag consists of a tube of material, one pair of flaps C, C' being formed by folding the ends of the bag on the diagonal lines D D shown in Fig. 5, and the other pair of flaps C, C' by folding over the corners of 60 the folds made by the first folding process.

The particular bag here described is of a familiar form of manufacture and when it leaves the factory is commonly closed at one end. To effect such a closure the four flaps 65 are brought together in proper relation and by gum, mucilage, or other like materials, they are attached together so as to form the bottom of the bag. The top is ordinarily left open. The material is then poured into 70 the bag at the top, when the four flaps are brought together at this point, whereupon they may be secured together in any desired manner. This closure of the top of the bag takes place after the bag has been filled. 75

With my invention the bag is brought into the complete form indicated in Figs. 4 and 5 before it is filled, that is to say, the bottom is not only permanently closed, but the flaps of the top are also in part permanently attached to each other in such way as to leave an opening into the bag somewhat as illustrated. This opening is in this case formed by gumming the three upper flaps together and leaving them separated from the lower 85 or innermost flap. Thus there is left an opening into the bag from one side, so to speak, or at an angle to its axis of length. This opening is also arranged so that two opposing surfaces are left and when the filling tube is removed these surfaces are brought together and are made to adhere to finish the package. These two surfaces are so arranged, it will be observed, that the tendency of the material in the bag is to close them or 90 force them together. A bag thus prepared, or prepared in any other manner, but having a filling aperture analogous to that of the bag illustrated, is then filled by introducing through such opening, preferably by means 100 of a filling tube, the material for which the bag is intended. As the material flows into the bag it rises in the same underneath one of the two sides of the opening and thus tends to, and eventually does close the filling opening. On the other hand, as the other side of this aperture is formed of overlapping parts 105 which are secured together so as to form, as it

were, a bridge, it cannot give way and hence, with one wall of the aperture being held in fixed position and the other being forced towards it by the material within the bag, it is 5 obvious that a very secure, self-closing filling aperture is formed. It is self-closing in the sense that the weight of the material within the bag causes it to close and remain closed as soon as the filling tube is removed. Of course, the opposite walls of this filling aperture should be secured together, which can be done by any adhesive material.

The material within the bag tends to close the two walls of the filling opening and they 10 may be made to adhere together or be otherwise secured together. The outer wall is formed as a bridge or arch, against which the inner wall of the opening sets. This latter inner wall is placed between the outer wall and the material. The direction 15 of the opening into the bag is tangential to its contents as distinguished from the opening into the bag in an ordinary open-mouthed bag. The walls of the opening may be pasted together or secured in any other convenient manner. The bag which I have shown 20 is a collapsible bag, although of course, it need not be so. It also presents a filled and flattened top and bottom, although this is 25 not indispensable. The adhesive material, if such be used, may be applied to the bag after it has been filled, or may be applied before it is filled, or in connection with the process 30 of filling.

Where I have spoken of the axis of the bag, 35 I mean that axis which is in substantial parallelism with the normal direction of filling of the bag if the filling aperture were of the ordinary construction. It is only another 40 way of stating that my bag is to be filled tangentially or at an angle to this axis wherever this axis may be and whether or not it is the short or long axis of the bag.

I claim:

1. A bag provided with a filling collapsible passage-way, one of whose walls is the relatively fixed exterior wall of the bag and the other of whose walls is a flap-like body adapted to be pressed against the first named wall by the weight of material within the edges of the two walls secured together and the passage-way lying between such secured edges.

2. A bag provided with a collapsible filling passage-way, which enters the bag at one end intermediate of its corners and substantially transversely to the axis of the bag.

3. A bag provided with a collapsible filling passage-way, which enters the bag at one end intermediate of its corners and substantially transversely to the axis of the bag, one wall of said passage-way comprising the relatively fixed exterior wall of the bag and the other a flap-like body adapted to be pressed thereagainst by the material within the bag the

edges of the two walls secured together and the passage-way lying between such secured edges.

4. A bag provided with walls to form a complete inclosure, said walls consisting of 75 two overlapping parts or materials, one of them relatively fixed and the two with edges secured together, and a passage way between such two overlapping parts or materials leading into the bag.

5. A bag provided with walls to form a complete inclosure, said walls permanently secured together, except two of said walls which consist of two overlapping parts disengaged at the upper end of the upper part, 80 but connected together along the edges so as to form a passage-way between the two overlapping parts leading into the bag and adapted to be closed by the pressure of the material within the bag against the inner overlapping part.

6. A valve bag having a square folded top and a filling opening in said top, said opening adjacent to and in position to be closed by one of the folds of said top, as set forth.

7. A paper valve bag having a top folded on diagonal lines and these folds folded over again, and a filling opening in said top, said opening adjacent to and in position to be closed by one of the primary folds of said top, 95 as set forth.

8. A valve bag, having a square folded closure at each end, the folds being permanently secured, and a valve controlled filling opening in one end, as set forth.

9. A paper valve bag, having a square folded closure at each end, the folds being permanently secured, and a filling opening in one end, said opening adjacent to and in position to be closed by one of said folds, as 105 set forth.

10. A paper valve bag, having a closure at each end folded on diagonal lines and these folds folded over again, the folds being permanently secured, and a valve controlled 110 filling opening in one end, as set forth.

11. A paper valve bag, having a closure at each end folded on diagonal lines and these folds folded over again, the folds being permanently secured, and a filling opening in 115 one end, said opening adjacent to and in position to be closed by one of the primary folds of the closure, as set forth.

12. A valve bag having a square folded top, and a filling opening extending laterally 120 inward between the folds of said top and in position to be closed by one of said folds, as set forth.

13. A paper valve bag, having a top folded on diagonal lines and these folds folded over 125 again, and a filling opening extending laterally inward between the folds of said top and in position to be closed by one of the primary folds, as set forth.

14. A valve bag, having a square folded 130

closure at each end, the folds being permanently secured, and a filling opening extending laterally inward between the folds of one end and in position to be closed by one of said 5 folds, as set forth.

15. A paper valve bag, having a closure at each end folded on diagonal lines and these folds folded over again, the folds being per-

manently secured, and a filling opening extending laterally inward between the folds of one end and in position to be closed by one of the primary folds of said end, as set forth.
